FOLDING CHAIR

Lewis C. Travers and George L. Morris, Gardner,
Mass., assignors to Calvin S. Greenwood, Gardner,
Mass.

Application February 7, 1934. Serial No. 710,094

2 Claims. (Cl. 155—117)

This invention relates to a folding chair of a type ordinarily termed "beach chairs" for use on beaches, lawns, porches, etc.

The principal objects of the invention are to provide in combination with a seat and back pivotally connected and movable together to positions in which the back assumes different angles to the horizontal and which back can be moved fully to horizontal position; a supporting means in the form of front and back legs which do not cross each other but which are provided with connections by which they can be held in their upstanding positions without danger of collapsing; and with no probability of pinching a finger; to provide a rearwardly folding supporting structure, foldable into a small compass, and to provide a structure having all the above mentioned features which can be folded, without the trouble of disconnecting any parts, in a length which is much less than has been the case heretofore and in fact so short that it can be placed crossways in an ordinary automobile behind the front seat for transportation.

Other objects and advantages of the invention will appear hereinafter.

Reference is to be had to the accompanying drawings, in which

Fig. 1 is a front view of a chair constructed in accordance with this invention;

Fig. 2 is a side view of the same;

Fig. 3 is a plan as indicated by the arrow 3 in Fig. 2;

Fig. 4 is a side view showing the back moved forward for folding;

Fig. 5 is a side view showing the parts folded into a small compass;

Fig. 6 is a sectional view on the line 6—6 of Fig. 2 showing the frictional arrangement for holding the chair in its adjusted position, and

Fig. 7 is a sectional view on the line 7—7 of Fig. 2, showing how the other pivots are made.

Chairs of the above mentioned character are generally made of a rather light construction and the back and seat are connected together while the supporting parts are usually made of cross legs which restrict the folding of the whole chair and necessitate its occupation of a considerable length when the chair is folded.

As people carry these chairs back and forth from beaches in automobiles, it is desirable to have a chair of this kind which can fold up into such compass that the length of the chair, when folded, is less than the width of an automobile so that it can be transported standing up on its edge behind the front seat of the car.

This is accomplished in this case by means of a particular type of frame structure comprising connected leg frames, one at each side of the chair. These leg frames include a pair of front legs 10, a pair of rear prop members 11, a pair of rear legs 12 and brace bars or members 13. The rear legs 12 are pivoted to the front legs 10 at the upper extremities of the latter and extend diagonally rearwardly and downwardly and are connected to the bottoms of the 10 prop members 11 by pivot links 15. The brace bars 13 are nearly horizontal and are pivoted at their opposite ends respectively to the front legs 10 and prop members 11. The prop members 11 are provided with outwardly projected 15 wooden pins 16 which rest on the rear legs 12 when the chair is set up and securely hold the latter in position and prevent its folding accidentally.

The leg frames are pivoted at their upper 20 ends to substantially horizontal arm pieces 14. On top of the arm pieces 14 are located the arms 21 of the chair. The front legs 10 are pivoted to the arm pieces 14 by pivots 22 and the prop members 11 are pivoted thereto by pivots 23. 25 These pivots 23 are made of long bolts which also pass through and pivot the sides of the back 24 of the chair. This back extends below the pivots 23 as well as above them and has a seat 25 pivoted to it by pivots 26. Also similar 30 pivots 26 are used to pivot this seat to a pair of links 27 which in turn are pivoted to the arm piece 14 by the pivots 22. The pivots 26 are of a general character shown in Fig. 7, this figure showing the pivot 26. The pivot stud 22, it will 35 be understood, is similar only longer because it has to go through the leg frame 10. These are ordinary free working pivot studs or rivets preferably having metal washers 29 to space the links 27 and leg frame 10 from the arm pieces 40 and allow free motion.

The pivot bolts 26 are intended for a purpose additional to the free pivoting of the parts. These bolts are fluted, as shown at 30, and the nuts 31 are tightened up right against a washer 45 so that they are tightly held together and the fluting prevents the turning of this pivot bolt in the seat 25. Therefore, the bolt can be tightened up sufficiently so as to supply a desired degree of friction to the parts and cannot turn, so as to 50 loosen in the nut, through continual movement of the back. Consequently, when in use, the desired amount of friction can be maintained and the back can be placed at any desired angle and it will not be forced out of that position unless 55

considerable pressure is applied to it. In other words, on account of this construction, the user can set the chair in a desired position and he will not be likely to work it into a different position 5 by any ordinary motion which he may make while sitting. Nevertheless it is perfectly easy to change it to any other angular position merely by the application of a sufficient amount of force.

It will be noted that when the back is adjusted

- 10 to the desired inclination, the seat is maintained in a plane parallel to itself, or the seat will not tilt or become misaligned with respect to the arm rests. In order to best obtain this advantage as to seating comfort and still provide for a compact
- 15 fold, it is preferred that the links 27 between their respective pivot points be of substantially the same length as the lower suspension portions of the back rest side rails 24 between the pivot points of the latter, and also that the distances between 20 the pivotal connections of the seat frame and arm rest members respectively be equal, so that the parts define a substantially parallelogram-shaped structure pivoted at its corners.

When it is desired to fold the chair, the back

- 25 is turned forwardly all the way around through an arc of 180° from its vertical position and, as shown in Fig. 5, the whole chair when folded will occupy a position of only a few inches longer than the back itself. It is made preferably so that the upper end of the back will fold beyond 30 the space normally located above the cross bar 12. This folding operation is fully shown in Fig.
- 35 5. It need not be described in full. The folded chair occupies a very small space and its thickness is not excessive. It can be stood upon edge in the space behind the front seat of an automobile. By this method of construction and folding there is no danger of the chair folding up accidentally and allowing the occupant to drop to 40 the floor.

It will be seen also that the back can be turned over to substantially a horizontal position and there is no danger of its folding up by any shifting of the weight of its occupant.

- 45 45. The chair is provided with a strong canvas seat 34 extending transversely across it and bound around the side members of the seat. Also there is a strip of canvas 35 extending along the seat and secured to the canvas 34 by cross stitching 50 36. It extends to the extreme rear thereof and up the back to the top thereof around which it passes and to which it is fastened. A heavy canvas piece 37 is secured across the back near the bottom thereof to furnish a more rigid support for the small of the back. At the bottom of the back is a bent strip 40 to complete the back frame and to permit the canvas in the seat to sag considerably before it interferes with the comfort of the

occupant when the chair is in horizontal position.

It will be seen, therefore, that the whole chair can be folded into very small compass lengthwise and that the back and seat are frictionally held in any adjusted position unless moved therefrom by some force greater than that usually provided by the motions of the body of the occupant.

Having thus described our invention and the advantages thereof, we do not wish to be limited to the details herein disclosed, otherwise than as set forth in the claims, but what we claim is:—

1. A folding chair comprising connected leg frames, one at each side of the chair, each leg frame having foldable front and rear legs pivotally connected at the front of the chair, arm rest members pivotally connected to the leg frames, a back pivotally connected to the arm rest members at the rear ends of the latter, a seat pivoted at the rear thereof to the lower extremity of the back, movable prop means between the back and leg frames when the chair is set up, bracing means between the front and rear legs, and means movably supporting the front of the seat in a manner to provide for adjustment of the seat and back 25 of the chair to different positions of use, said means including suspension links connecting the forward portions of the seat and the arm rest members, said links together with the lower extremity of the back, the arm rest members, and 30 seat frame defining a substantially parallelogram-shaped structure pivoted at its corners.

2. A folding chair comprising front and rear legs, the rear leg being pivoted at the front leg adjacent the upper extremity of the latter, arm 35 rest members pivotally connected to the upper ends of the front legs, a seat, a back rest frame having side rails pivotally connected to the rear ends of the arm rest members and extending downwardly and pivotally connected at their 40 lower ends to the seat, prop members at the sides of the chair pivotally connecting the arm rest members and the back rest side rails and extending downwardly and adapted to be supported by the rear legs when the chair is set up, bracing 45 means between the front and rear legs, and means swingably supporting the seat for backward and forward movement with respect to the leg frames and to conform with the inclination of the back, said means including suspension links pivoted 50 at their lower ends to the front extremity of the seat and at their upper ends to the arm rest members and upper ends of the front legs, said links together with the lower extremities of the back rest side rails, the seat frame and arm rest members defining a substantially parallelogram-shaped structure pivoted at its corners.
